Mark A. Anderson,
ATTORNEY.

UNITED STATES PATENT OFFICE.

PASQUALE RACCIO, OF NEW HAVEN, CONNECTICUT, ASSIGNOR, BY DIRECT AND MESNE ASSIGNMENTS, TO THE RACOLOCK COMPANY, OF NEW HAVEN, CONNECTICUT, A CORPORATION OF CONNECTICUT.

LATCH.

1,351,686.

Specification of Letters Patent. Patented Aug. 31, 1920.

Application filed August 5, 1919. Serial No. 315,472.

To all whom it may concern:

Be it known that I, PASQUALE RACCIO, citizen of the United States of America, and resident of New Haven, in the county 5 of New Haven and State of Connecticut, have invented certain new and useful Improvements in Latches, of which the following is a specification.

This invention relates to latches, and particularly to those for use on doors of automobiles, although it is also of utility in connection with other doors.

The latches should, of course, be made right and left, for doors on different sides 5 of an automobile, but I will describe a single form of latch and those skilled in the art will understand the changes necessary to make it adaptable for use on the opposite side of an automobile.

20 An object of this invention is to produce novel means whereby a latch is held retracted when a door is open, and whereby the said latch is released upon closing of a door so that the latch may project and engage an escutcheon to hold the door closed.

25 The latch operates without the application of force, and the door need not be slammed to insure action of the latch.

30 A still further object of this invention is to provide a novel latch releasing device which coacts with a member so designed as to be actuated by the movement of the latch.

35 A further object of this invention is to produce a latch which may be operated in an independent manner by a handle or lever projected above the latch, the said invention also including means for retracting the handle and means for urging the latch outward.

40 With the foregoing and other objects in view, the invention consists in the details of construction and in the arrangement and combination of parts to be hereinafter more fully set forth and claimed.

45 In describing the invention in detail, reference will be had to the accompanying drawings forming part of this specification wherein like characters denote correspond-

ing parts in the several views and in which—

Figure 1 illustrates a view in elevation of the mechanism of the latch.

Fig. 2 illustrates an edge view thereof.

Fig. 3 illustrates a sectional view thereof.

Fig. 4 illustrates detail view of the latch.

Fig. 5 illustrates top plan view of the latch holding the bolt.

Fig. 6 is an edge view of the bolt cam.

In these drawings 10 denotes a side of 60 the latch casing having an escutcheon plate 11, with an aperture 12 through which the latch bolt 13 projects. The said bolt has a recess 14 and an elongated aperture 15, in which latter a stud 16 of a cam 17 projects, the end of the cam lying in the recess 14 of the bolt. The bolt is further provided with a recess 16 in its side, which has a shoulder 17 at one end, and the shoulder may be engaged by an operating lever 18 65 projecting through the top of the casing, the said lever being pivoted on the stud 18 carried by the casing. Anti-friction rollers 19 engage the upper and lower surfaces of the bolt and constitute guides by which the 70 said bolt is held in proper position.

A spring 20 has one end anchored to a stud 21, and the said spring bears against the lever so that the action of the spring tends to force the lever in a direction to move the lever toward the stop 20.

The spring 22 has an end bearing against the end of the bolt and the opposite end of the said spring is anchored to the stud 23. The action of the spring 22 is to urge the bolt outwardly when released (as will presently appear). The rollback 17 may have an aperture 24 for the reception of a spindle, by which the rollback may be oscillated or

partially rotated, and when this means is supplied for actuating the rollback, handles may be applied to the spindle and the door lock may be actuated in this manner, the lever in such case being omitted, although both latch operating means may be

90 present and they may be operated independently.

The rollback has a shoulder 25 engageable

by a trigger 26, and the trigger engages the lever and operates the lever under certain conditions or is operated by the lever under other conditions. In the event of the lever 5 being omitted, the spring 20 would be extended to bear against the trigger so that it would be under the influence of the said spring, but this construction would only be employed if provision were made for operating the rollback 17 by means other than the lever.

The trigger 26 is formed as a part of a bolt 27, which is mounted to slide with relation to the casing and an end of the bolt is 15 adapted to project through an aperture 28 of the casing. The bolt terminates in a beveled or camming end 29, which projection is adapted to engage a camming lug 30 on the keeper plate 31, and the keeper plate 20 is secured in a suitable manner to the door frame. The keeper plate has a latch guide 32, which consists in an inwardly extending flange at the side of an aperture 33 in said keeper plate. The bolt 27 has a slot 27^a to 25 receive a guide 27^b and a spring 27^c lies in the slot between the stop and the end 27^d of the bolt and presses said bolt outwardly.

The operation of the device will, it is thought, be understood from the foregoing 30 description, but it may be proper to add that when the latch is retracted and the door is opened, the trigger is forced by the spring 27^c into engagement with the shoulder 25 and the latch is held retracted during the 35 time the door is open. This is desirable, as it removes any projecting device on the door which might come in contact with clothing. When the door is closed the trigger bolt is operated by reason of this engagement with

the cam lug 30 and the trigger releases the 40 shoulder 25, permitting the springs to reset the bolt in locked position, and this relation of parts will be maintained until the door is again opened.

I claim:

1. In a latch, a casing, a bolt slidable therein, means for urging the bolt outwardly, a rollback having a shoulder, means for operatively connecting the rollback and latch whereby they move in unison, a trigger bolt slidable in the casing and projecting therefrom, means for holding the trigger bolt projected, means for retracting the trigger bolt, a trigger carried by the trigger bolt and adapted to engage the shoulder 50 of the rollback when the bolt is retracted, and means for retracting the bolt.

2. In a latch, a casing, a bolt slidable therein and adapted to project therefrom, a rollback mounted in the casing and operatively connected to the bolt, said rollback having a shoulder on its outer edge, a latch bolt slidably mounted in the casing and adapted to project therefrom, means for urging the trigger bolt outwardly, a trigger 60 carried by the said bolt and adapted to engage the shoulder of the rollback when the bolt is retracted, a member adapted to engage the projecting end of the trigger bolt to force it inwardly to cause a disengagement of the latch and the rollback, a lever pivotally connected to the casing and extending past the bolt in engagement therewith to operate said bolt, means for urging the bolt outwardly, and means for pressing 65 the lever for swinging it on its pivot when the bolt is released.

PASQUALE RACCIO.
